[57] CLAIM

The ornamental design for a shoe sole, as shown and described.

DESCRIPTION

FIG. 1 is a left side elevational view of a shoe sole showing our new design;

FIG. 2 is a right side elevational view thereof;

FIG. 3 is a bottom plan view thereof;

FIG. 4 is a front perspective view thereof;

FIG. 5 is a rear perspective view thereof;

FIG. 6 is a bottom plan view of a shoe sole showing a second embodiment of our new design.

The broken line showing of a shoe upper in FIGS. 1-6 is environmental only and forms no part of the claimed design.
